[57] CLAIM

The ornamental design for a windshield wiper blade, as shown and described.

DESCRIPTION

FIG. 1 is a perspective view of a windshield wiper blade showing my new design;

FIG. 2 is a left side view thereof;

FIG. 3 is a top view thereof;

FIG. 4 is a front view thereof; and,

FIG. 5 is a bottom view thereof.

The side opposite to FIG. 2 is a mirror image thereof. The windshield wiper blade is shown broken away in the middle section in FIGS. 1, 3, 4 and 5 to indicate indeterminate length.
